UNITED STATES PATENT OFFICE

2,315,900

CIGARETTE CASE

Robert N. Lupfer, Springfield, Ohio, assignor to
The Springfield Leather Products Co., Spring-
field, Ohio, a corporation of Ohio

Application September 27, 1940, Serial No. 358,678

2 Claims. (Cl. 206—41)

This invention relates to cases in which packaged cigarettes can be carried and be dispensed therefrom as desired.

An object of the invention is to provide a cigarette case for enclosing packaged cigarettes having a dispensing opening which may be closed by a rigid slide member suitably retained and guided in proper relation with the dispensing opening.

Another object of the invention is to provide a cigarette case for enclosing packaged cigarettes wherein an end wall of a flexible case is rigidly supported, and a slide is carried by the rigid supporting wall in a slidable manner to permit opening and closing of a dispensing opening in the flexible case.

A further object of the invention is to provide a flexible cigarette case for enclosing packaged cigarettes wherein an end wall is provided with a rigid support which is attached to the wall in such a manner that a slide may cooperate therewith for closing a dispensing opening.

Another object of the invention is to provide a leather case for enclosing packaged cigarettes wherein a metal slide and guide means is provided in operative association with a dispensing opening for opening and closing the same.

A still further object of the invention is to provide a metal support upon an end wall of a flexible cigarette case and provide means for securing the metal support to the flexible end wall in such a manner as to expose a minimum amount of the metal, and wherein the metal support provides means for slidably guiding and supporting a slide member for closing a dispensing opening in the case, and wherein the slide is provided with a manipulator extending through the support.

Further objects and advantages of the present invention will be apparent from the drawing and a reading of the description which follows.

In the drawing:

Figure 1 is a perspective elevational view of a cigarette case embodying features of this invention, and shows a slide in the open position for dispensing cigarettes;

Figure 2 is a perspective elevational view similar to Figure 1, the slide, however, being in closed position;

Figure 3 is a longitudinal cross-sectional view taken along line 3—3 of Figure 1;

Figure 4 is a transverse cross-sectional view taken along line 4—4 of Figure 1;

Figure 5 is a horizontal cross-sectional view taken along line 5—5 of Figure 1 and looking upwardly in the direction of the arrows.

This invention is adapted for use in connec-

tion with carrying packaged cigarettes. It is well-known that the paper package in which cigarettes are packed and sold is insufficient support for the cigarettes when they are carried upon the person. The package becomes damaged and destroys the cigarettes. A convenient manner for dispensing cigarettes from the original package consists of tearing or cutting one end of the package in such a manner as to expose several cigarettes. Such a manipulation of the end of a package provides a substantially rectangular opening through which cigarettes may be dispensed from the original package, the remaining cigarettes being retained within the package in an attempt to retain their shape and condition while being carried in the pocket of the person.

This invention permits a cigarette package, prepared as aforementioned, to be placed in a container or case with the prepared end adjacent 20 a dispensing opening in the case. A slidable closure member is provided for opening and closing the dispensing opening of the case to permit cigarettes to be dispensed from the case in the same manner as from the original package prepared as aforementioned. It is to be understood, however, that the cigarettes can be removed from the original package and be placed within the case for protection and from which they can be dispensed in the same manner as from an original package.

The cigarette case of this invention consists of a substantially rectangular case 10 which can be manufactured from any suitable material such as metal, leather or plastic. It is more convenient, however, to manufacture the case 10 from a flexible material such as leather since this material will more or less conform to the pocket of a person, it is light in weight, while providing protection for cigarettes contained therein. The invention is thus disclosed in its preferred form as being applied to a leather cigarette case.

The case 10 consists of side walls 11, edge walls 12 and end walls 13 and 14, respectively. Means are provided for gaining access to the interior of the case 10 by placing a zipper 15 within the edge walls 12 and the end wall 13. A suitable cut-out portion 16 is provided in the edge walls 12 and the end wall 13 to permit operation of the zipper 15 which is stitched to the edge of the cut-out portion 16 as at 17.

The top wall 14 of the cigarette case 10 is provided with a dispensing opening 20 through which cigarettes contained within the case 10 may be dispensed as desired. The dispensing opening 20 is adapted to be closed by means of a slide 21

which is provided with a manipulator knob 22. The slide 21 is slidably supported in guided relation upon a rigid support and guide member 23.

The guide member 23 has longitudinally extending guide rails 24 integrally formed as a part of the guide member 23 by bending opposite parallel edges of the guide member 23 angularly with respect to the plane of the member 23 whereby a substantially U-shaped channel is provided. The slide member 21 is positioned between the guide rails 24 and is retained in guided relationship therewith by the manipulator knob 22, which extends through an elongated slot 25.

The elongated slot 25 positioned within the guide member 23 is arranged with an upwardly extending flange 26 which is adapted to extend through a longitudinally positioned slot 27 provided in the end wall 14 of the case 10. The flange 26 of the slot 25 is formed over the edge of the slot 27 in the end wall 14, whereby the guide member 23 is retained adjacent the wall 14. The guide member 23 and the slide 21 are positioned adjacent the inner face of the wall 14 whereby an exposed metal edge of a flange 28 and the flange 26 are the only exposed metal parts of the case except for the slide 21 and the manipulator knob 22. The flange 26 is formed over an edge of the dispensing opening 20, this flange in cooperation with flange 26 providing the means for retaining the guide 23 and the slide 21 adjacent the wall 14.

The manipulator knob 22 is secured to the slide 21 by any suitable means, such as by staking the end 29. This manipulator knob 22 extends through the eyelet formed by the slot 25 and the formed flange 26 and terminates in an enlarged head 30, the edges of which overlap parallel longitudinal edges of the eyelet, whereby the slide 21 is supported adjacent the rigid support and guide member 23. The eyelet formed by the slot 25 and the formed flange 26 provides means for limiting the longitudinal movement of the manipulator 22, and thus the slide 21.

As heretofore mentioned, the cigarette case 10, which includes the wall 14, is constructed from a flexible material such as leather. The guide member 23 provides a rigid support for the flexible wall 14 whereby the rectangular shape of the wall 14 is retained when the case is being carried upon the person, since the guide 23 covers substantially the entire area of the wall 14. When the slide 21 is advanced to its forward or closed position, as shown in Figure 2, the slide provides the means for retaining the end of the case having the dispensing opening therein in proper configuration. If desired, to obtain additional stiffness for the side and edge walls of the case 10, a reinforcement strip 31 may be positioned adjacent the inner faces of the respective walls. This, however, is not a necessity and is suggested only if it is desired to provide a firm and rigid cigarette case.

It may readily be seen that the device of this invention is extremely simple to manufacture and can be produced at low cost. Further, it can be seen that a flexible cigarette case, such as constructed of leather, can be provided with a rigid wall adjacent which a slide may be positioned for closing a dispensing opening. Furthermore, the slide and guide member for the same provide a rigid support which may be easily and inexpensively attached to an end wall of the flexible case wherein the attaching means are of little consequence in exterior showing thereof, but which may add considerable to the decorative qualities of the case.

Having thus fully described my invention, what I claim as new and desire to secure by Letters Patent is:

1. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing opening located adjacent to one side of the case, the inner wall portion of said double end wall terminating at its opposite edges in a pair of guide rails, a closure plate of relatively stiff material confined in the case in face contact with the inner surface of said inner wall portion, said plate being guided in the lateral direction by said rails, said closure plate having an operating element projecting through the end wall and accessible on the outside of the case, and a flat reenforcing member carried by the side wall adjacent to the dispensing opening and substantially the same width as the said side wall.
2. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing open located adjacent to one side of the case, the inner wall portion of said double end wall terminating at its opposite edges in a pair of guide rails, a closure plate of relatively stiff material confined in the case in face contact with the inner surface of said inner wall portion, said plate being guided solely in the lateral direction by said rails, said closure plate having an operating element projecting through the end wall and accessible on the outside of the case, and a flat reenforcing member carried by the side wall adjacent to the dispensing opening and substantially the same width as the said side wall.
3. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing open located adjacent to one side of the case, the inner wall portion of said double end wall terminating at its opposite edges in a pair of guide rails, a closure plate of relatively stiff material confined in the case in face contact with the inner surface of said inner wall portion, said plate being guided in the lateral direction by said rails, said closure plate having an operating element projecting through the end wall and accessible on the outside of the case, and a flat reenforcing member carried by the side wall adjacent to the dispensing opening and substantially the same width as the said side wall.
4. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing open located adjacent to one side of the case, the inner wall portion of said double end wall terminating at its opposite edges in a pair of guide rails, a closure plate of relatively stiff material confined in the case in face contact with the inner surface of said inner wall portion, said plate being guided solely in the lateral direction by said rails, said closure plate having an operating element projecting through the end wall and accessible on the outside of the case, and a flat reenforcing member carried by the side wall adjacent to the dispensing opening and substantially the same width as the said side wall.
5. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing open located adjacent to one side of the case, the inner wall portion of said double end wall terminating at its opposite edges in a pair of guide rails, a closure plate of relatively stiff material confined in the case in face contact with the inner surface of said inner wall portion, said plate being guided solely in the lateral direction by said rails, said closure plate having an operating element projecting through the end wall and accessible on the outside of the case, and a flat reenforcing member carried by the side wall adjacent to the dispensing opening and substantially the same width as the said side wall.
6. A cigarette dispensing case made of flexible material and shaped to receive and hold a package of cigarettes snugly therein, said case having a continuous slide fastener opening in one end and in the adjacent portions of the side walls to permit insertion of a package of cigarettes, the other end of the case being provided with a double end wall having a dispensing open located adjacent to one side of the case, the inner wall portion of said double end wall terminating at its opposite edges in a pair of guide rails, a closure plate of relatively stiff material confined in the case in face contact with the inner surface of said inner wall portion, said plate being guided solely in the lateral direction by said rails, said closure plate having an operating element projecting through the end wall and accessible on the outside of the case, and a flat reenforcing member carried by the side wall adjacent to the dispensing opening and substantially the same width as the said side wall.
